UNITED STATES PATENT OFFICE

162,682

BRASSIÈRE OR SIMILAR ARTICLE

Morris Newman, New York, N. Y., assignor to Surprise Brassiere Co. Inc., New York, N. Y., a corporation of New York

Application December 31, 1949, Serial No. 6,948

Term of patent 14 years

(Cl. D20—4)

To all whom it may concern:

Be it known that I, Morris Newman, a citizen of the United States of America and resident of the city, county, and State of New York, have invented a new, original, and ornamental Design for a Brassière or Similar Article, of which the following is a specification, reference being had to the accompanying drawing, forming a part thereof, and showing Fig. 1 a front view of a brassière embodying my design, and in Fig. 2 a perspective view of the brassière as it appears when worn.

I claim:

The ornamental design for a brassière or similar article, as shown.

MORRIS NEWMAN.
